WINDOW SASH UNIT

Christian M. Verhagen, Elkhart, Ind., assignor
to The Adlake Company, Chicago, Ill., a cor-
poration of Illinois

Application April 17, 1947, Serial No. 742,166

6 Claims. (Cl. 20—56.5)

1

This invention is concerned with improvements in a multiple glass window pane structure of the type having a heat insulating space between the panes.

An object of the invention is to provide a window pane unit comprising two or more panes of glass mounted in a channel-like frame and provided with a sealing gasket having a rib portion spacing the panes from each other, which unit has incorporated therein a breather member extending through the sealing gasket and a breather path leading from said breather member to an outer surface of the unit for venting the otherwise closed air space between the spaced panes of glass.

It is a more specific object of the invention to provide a window pane unit having multiple panes of glass supported in spaced relation by a sealing gasket which sealing gasket has incorporated therein a section constituting a breather member and means cooperating with the breather section to provide a breather path extending from the breather section to an outer side of the unit.

It is another object of the invention to provide a window pane unit having multiple panes of glass supported in spaced relation by a sealing gasket which sealing gasket has incorporated therein a section constituting a breather member, and means including a longitudinally extending groove in the sealing gasket cooperating with the breather section to provide an indirect breather path extending from the breather section to an outer side of the unit.

It is a further object of the invention to provide in a multi-pane sash unit a sealing and spacing gasket having incorporated therein a needle-like breather member and cooperating means providing a breather path leading from the otherwise closed air space between the spaced panes to outside of the unit.

These and other objects of the invention will be apparent from a description of the preferred form thereof which is shown by way of illustration in the accompanying drawings, wherein:

Fig. 1 is an elevation of a sash unit embodying the principles of the invention;

Fig. 2 is a perspective view to an enlarged scale of a corner portion of the unit illustrating the corner joint of the channel frame;

Fig. 3 is a section on the line 3—3 of Fig. 1 to an enlarged scale;

Fig. 4 is a section on the line 4—4 of Fig. 1 to an enlarged scale;

Fig. 5 is a sectional view on the line 5—5 of Fig. 4;

2

Fig. 6 is a perspective view of a portion of the sealing strip;

Fig. 7 is a perspective view of the breather member; and

Fig. 8 is a section transversely through a sealing strip illustrating a modified form of breather member.

Referring to Figs. 1 to 7 of the drawings, the sash unit illustrated comprises a generally U-shaped frame or edge encompassing member 10 formed by connecting at their corners the four channeled sections 11, 12, 13 and 14.

The preferred corner construction is particularly illustrated in Fig. 2 which shows the corner joint between frame sections 12 and 13. It comprises a projecting lug or tongue 15 formed on the base portion 16 of the mitered corner of the section 12 and a projecting tongue 17 formed on the base portion 18 of the mitered corner of the section 13. The tongue 17 is provided with a slot 19 along the meeting line of the base portions 16 and 18 of the sections 12 and 13 which is of a size sufficient to snugly receive the tongue 15. The sections 12 and 13 are assembled in abutting relation with the tongue 15 projecting through the slot 19 and the tongues 15 and 17 are then bent down flat against the outside faces of the base portions 18 and 16 of the channel members 13 and 12, respectively. The connections at each corner of the frame 10 are identical.

Two panes of glass 20 and 21 are positioned in the frame member 10 in spaced relation with their outside faces in engagement with inturned edges 22 and 23 of the legs or flanges 24 and 25, respectively, of the frame member 10. The panes 20 and 21 are spaced from each other to provide an insulating air space 26 between their inside surfaces. They are held in spaced relation by a rib-like portion 27 of a sealing gasket 28 which surrounds the lateral edges of the panes.

The sealing gasket 28 is generally T-shaped provided with a generally flat transversely extending top portion 29 and the rib-like leg or stem portion 27. The rib portion 27 is provided with outwardly sloping faces 30 and 31 and a lower generally concave face 32. When the rib portion 27 is positioned between the glass panes 20 and 21, the tapered leg-like formations 33 and 34 formed by the tapered and curved cross section of the rib 27 are compressed or moved toward each other to bring a substantial portion of the tapered surfaces 30 and 31 into surface engagement with the inner surfaces of the glass panes 20 and 21, thus sealing and enclosing the space 26 between the panes. The laterally extending side portions 35 and 36 of the top por-

tion 29 of the sealing gasket 28 are positioned between the base 18 and the lateral edges 37 and 38 of the panes 20 and 21. The side portions 35 and 36 provide a seal between the edges 37 and 38 of the panes 20 and 21 and the frame 10.

The sealing gasket 28 has incorporated in its length a relatively short breather member or block 39 (Fig. 7) which is of the same cross-sectional configuration as the sealing gasket 28 and which is preferably formed of porous rubber of the type having minute passageways therethrough which are sufficient to permit passage of air. The breather member or block 39 is initially vulcanized in integral relation with the sealing gasket 28 and forms an integral portion thereof so that the sealing gasket completely surrounds the panes 20 and 21 on all four sides.

The sealing gasket 28 is provided with a longitudinal groove 40 which is located in the outer surface of the top portion 29 and which extends completely around the sealing gasket 28 except for the portion of the same which constitutes the breather member 39.

The frame 10 is provided with a transverse groove 41 on the inner face of the base portion 18 of the frame member 13, at a point spaced from the porous member 39 which when the sealing gasket 28 is arranged with its top portion 29 in contact with the base 18 provides a passageway from the groove 40 outwardly beyond the lateral portions 35 and 36 of the sealing gasket 28 and into communication with the space formed between the outer surfaces of the panes 20, 21 and the inner surfaces of the legs 24, 25 of the frame member 13. One leg 24 of the frame is provided with an opening 42 at the edge for communication with the outside atmosphere which opening may be conveniently formed by straightening a small portion of the turned-in edge 22. By means of this construction air is permitted to pass from the air space 26 between the panes 20 and 21 through the breather block 39 into the groove 40 in the sealing gasket 28, along the groove 40 to the transverse groove 41, along the groove 41 and through the opening 42 to the outside atmosphere, thus providing an indirect path for venting the space 26 and eliminating the formation of moisture due to unequal temperature conditions.

In Fig. 8 a modified sealing gasket construction is illustrated. In this construction the sealing gasket is formed of solid rubber and is provided at one point with a hypodermic needle type of breather member 44. The breather member 44 extends through the gasket 43 from the top thereof and connects a longitudinal groove 45 in the top of the gasket 43 with the air space between the panes by a minute passageway. The breather member 44 is located at a point spaced from the transverse groove which connects with the outlet opening.

A further modification consists of substituting for the transverse groove 41 in the frame 10 of the preferred form, a transverse groove in the sealing gasket 27 to provide a transverse passageway connecting the longitudinal groove 40 with the space between the outer surface of the panes and the channels and thence through the opening 42 provided in the edge of the frame to the outside atmosphere.

While specific details of construction and materials have been referred to in describing the illustrated embodiments of the invention, it will be understood that other details of construction

and other materials may be resorted to within the spirit of the invention.

I claim:

1. A multiple glass sash unit that includes a frame comprising channel-like sections, two panes of glass arranged in said frame, a sealing gasket spacing said panes from each other and from portions of said frame, said frame having inwardly bent edges in engagement with the outer surfaces of said panes and a breather member in said sealing gasket, said sealing gasket having a longitudinal groove providing a breather path, and said frame being formed with a cooperating transverse breather path connecting said breather member with the atmosphere on one side of said unit.

2. A multiple glass sash unit as claimed in claim 1 wherein said breather member consists of a relatively short section of porous material incorporated in integral relation in said sealing gasket.

3. A multiple glass sash unit as claimed in claim 1 wherein said transverse breather path is provided by a transverse groove formed in said frame at a point spaced from said breather member and an opening between a leg of said frame and the outside surface of the adjacent pane of glass.

4. A multi-glass sash unit that includes a frame comprising channel-like sections, two panes of glass positioned in spaced relation within said frame, a generally T-shaped rubber sealing gasket having the leg thereof positioned between said panes of glass adjacent the edges of the same and having the transverse top thereof positioned between the outer edges of said panes and the base portion of the top channel-like section, said gasket extending completely around the edges of said panes and said gasket being provided with a relatively short integral section of porous rubber material, said gasket having a longitudinal groove extending along the outer surface of the top portion thereof and said unit being provided with a transverse groove forming a passageway at a point spaced from said porous section, said frame having turned-in edges in engagement with the outer surface of said panes, and one of said turned-in edges being provided with an opening adjacent said transverse groove whereby the space between said panes is vented.

5. A multiple glass sash comprising two panes of glass, a sealing gasket spanning the lateral edges of said panes and having a compressible rib portion extending between said panes to space said panes from each other and provide an insulating air space between the same, an edge enclosing frame surrounding said panes and having side portions extending a short distance inwardly along the edges of said panes, said side portions having inwardly directed edges engaging the outer surfaces of said panes, a breather member in said sealing gasket, and a passageway between said sealing gasket and the interior of said frame forming an air path from said breather member to outside said unit, said passageway having a portion thereof extending along a side portion of said frame and terminating at the edge thereof.

6. A multi-glass sash unit that includes a frame having channel-like sections, two panes of glass positioned in spaced relation with said frame, a generally T-shaped rubber sealing gasket having the leg thereof positioned between said panes of glass adjacent the edges of the same and having the transverse top thereof positioned between the

outer edges of said panes and the base portion of a frame section, said gasket extending completely around the edges of said panes, said gasket being provided with a relatively short integral section of porous material, said gasket having a longitudinal groove extending from said porous section along the outer surface of the top portion of said gasket, said unit having a cooperating transverse groove communicating with said longitudinal groove, said frame having inwardly directed edges in engagement with the outer surface of said panes, and one of said edges being provided with an opening communicating with

said transverse groove whereby the space between said panes is vented.
